UNITED STATES PATENT OFFICE.

ERWIN NEUHOLD, OF FRIEDENAU, NEAR BERLIN, GERMANY, ASSIGNOR TO THE FIRMA DEUTSCHE TELEPHONWERKE G. M. B. H., OF BERLIN, GERMANY.

IMPULSE-TRANSMITTER.

1,021,259.

Specification of Letters Patent. Patented Mar. 26, 1912.

Application filed April 22, 1910. Serial No. 557,092.

To all whom it may concern:

Be it known that I, ERWIN NEUHOLD, engineer, a subject of the King of Hungary, and resident of Friedenau, near Berlin, Germany, have invented certain new and useful Improvements in Impulse-Transmitters, of which the following is a specification.

This invention relates to a device for sending current, the operation of which is automatically determined by the choice of one of several keys. Such current senders are required, for example, at the subscribers' stations of automatic telephone exchange systems, where, as so-called number switches, they serve to produce in the line a number of current impulses corresponding to the number of the desired subscriber. Switches of this kind are known which are operated by means of a series of holes corresponding to the numbers 1 to 9 and 0, the finger being inserted in the corresponding hole and then serving as a projection to limit the movement of the switch. This way of working is not without danger since it is not impossible to hurt the finger. Other devices have therefore been proposed which consist essentially of one or more keys, the lifting of which is limited by a plug set in one of a series of holes. This method of working is fiddling and easily gives rise to errors.

According to the invention the problem is solved by driving the contact device by keys which have a certain free movement. When used these alter the position of stops so that the latter limit the motion of a contact device sooner or later according to the key used and so automatically cause contact to be made the desired number of times.

In the drawing one form of construction is shown, Figure 1 being a sectional side view, and Fig. 2 a partial front view.

In the casing *x* on the base plate *y* is a frame *b*, *f*, *g* revolvable upon an axis *c*. The bars *b* of this frame are bent upward at the free end *t* and each there carries on pins *i*, *k* a bar *t'* with a finger plate *d*. This bar has slots in which the pins *i*, *k* move and is drawn into the upper position by a spring *h*. The frame itself is normally held in the position illustrated (the upper position) by a spring *z*. Upon it is secured a toothed arc *m* which drives the shaft *a* of the cam disk *p* through a pinion *n*. The cam disk is connected with the pinion or with the shaft *a* by a running pawl *o* engaging on teeth in its

interior so that it only turns with the axis in the direction opposite that shown by the arrow. In such turning the cam projections operate upon contact springs *u*, *v* through the medium of a pivotal projection *s* which, if the cam disk should happen to be turned backward, yields so that the springs *u*, *v* are not brought into contact.

Now if a key *d* is depressed the corresponding bar *t'* first moves down and in consequence of the sloping slots moves toward the right in Fig. 1, so that the spring *h* is tensioned. This motion brings a projection *r* on the bar *t'* so far forward that when the whole frame is depressed it strikes upon a step of the strip *e*. The frame *b*, *f*, *g* thus has a larger or smaller oscillation which through the toothed arc *m* produces a corresponding movement of the pawl *o* and on the release of the key a corresponding revolution of the disk *p*. On pressing the key farthest to the left in Fig. 2 the frame is given its greatest movement. In this case the springs *u*, *v* are pressed together by the disk *p* 10 times so that 10 current impulses are sent. The step 9 causes 9 current impulses. The key corresponding to it moves down simultaneously with the first but in general does not strike the strip *e*. It only strikes the strip when its own finger piece *d* is depressed and so its projection *r* moved forward. The other keys work in the same way. When the key depressed is released the movable bar *t'* returns to its position of rest. The making of contact between *u* and *v* is caused when the frame returns, which motion is due to the spring *z* and is retarded by an escapement *w*.

Having now particularly described and ascertained the nature of my said invention and in what manner the same is to be performed, I declare that what I claim is:

1. An impulse transmitter of the character described, comprising a movable member, a contact mechanism to be operated by said member, a plurality of keys for moving said member and adapted to move relatively with respect to it, and a plurality of stops co-operating with said keys, substantially as and for the purpose set forth.

2. An impulse transmitter of the character described, comprising a movable member, a spring to be tensioned by the movement of said member into its working position and to return said member after re-

lease into its position of rest, a contact mechanism to be operated by said member, a plurality of keys for moving said member and adapted to move relatively with respect 5 to it, and a plurality of stops coöoperating with said keys, substantially as and for the purpose set forth.

3. An impulse transmitter of the character described, comprising a movable member, a spring to be tensioned by the movement of said member into its working position and to return said member after release into its position of rest, a contact mechanism to be operated by said member, 10 so as to close its circuit only on the return movement of said member, a plurality of keys for moving said member and adapted to move relatively with respect to it, and a plurality of stops coöoperating with said 15 keys, substantially as and for the purpose set forth.

4. An impulse transmitter of the character described, comprising a pivotally mounted frame, a contact mechanism to be 20 operated by said frame, a plurality of keys provided on said frame and adapted to move relatively with respect to it, springs to counteract the relative movement of said 25 keys, projections on said keys and a plu-

rality of stops limiting the movement of 30 said frame by standing in the way of the respective pressed key, substantially as and for the purpose set forth.

5. An impulse transmitter of the character described, comprising a pivotally mounted frame, a toothed sector on said frame, a spindle provided with a pinion gearing with said sector and a spring to be tensioned by the movement of said frame into its working position and to return said 40 frame into its position of rest, a contact mechanism to be operated by said spindle so as to close its circuit only on the return movement of said frame, a plurality of keys provided on said frame and adapted to 45 move relatively with respect to its springs to counteract the relative movement of said keys, projections on said keys and a plurality of stops limiting the movement of said frame by standing in the way of the 50 respective pressed key, substantially as and for the purpose set forth.

In testimony whereof I affix my signature in presence of two witnesses.

ERWIN NEUHOLD.
